UNITED STATES PATENT OFFICE

2,475,303

DECORATIVE COVER FOR TELEPHONE
HANDPIECESCalvin H. Allen and Mary E. Allen, Oakland,
Calif., assignors to Colorphone, Inc.

Application August 26, 1946, Serial No. 693,124

2 Claims. (Cl. 179—179)

1

This invention relates to decorative or protective covers for instruments such as telephone transmitter-receiver units.

An object of the invention is to provide a two-piece semi-rigid envelope, for instruments of the character described, which is possessed of minimum bulk so that the overall dimensions of the instrument are not increased to the point where it becomes unwieldy.

Another object of the invention is to provide an envelope of the character described embodying an improved joint for connecting the sections together and including concealed latch elements for preventing accidental separation of the sections.

A further object of the invention is to provide a device of the class referred to which will not detract from the outward appearance of the instrument with which it is used.

The invention possesses other objects and features of advantage, some of which, with the foregoing, will be set forth in the following description of the preferred form of the invention which is illustrated in the drawings accompanying and forming part of the specification. It is to be understood, however, that variations in the showing made by the said drawings and description may be adopted within the scope of the invention as set forth in the claims.

Referring to the drawing:

Figure 1 is a top plan view of the cover of my invention showing it applied to a transmitter-receiver unit.

Figure 2 is a side elevational view of the structure shown in Figure 1.

Figure 3 is a top plan view of the cover alone.

Figure 4 is a vertical sectional view taken in the plane indicated by the line 4—4 of Figure 3.

Figure 5 is a vertical sectional view taken in the plane indicated by the line 5—5 of Figure 4.

The decorative or protective cover of my invention is particularly designed for use with instruments such as, for example, the telephone hand set shown which comprises a microphone transmitter unit 6 and an earphone receiver unit 7 suitably mounted in and comprising part of a housing which includes an interconnecting comparatively slender handle portion 8. The cover, substantially completely enclosing the instrument except for openings exposing the faces of the transmitter and receiver comprises a two-piece shell, preferably constructed of molded plastic, each section of which is a complementary-shaped substantial duplicate of the other provided with a cavity which includes substan-

2

tially circularly-shaped depressions 9 and 11, for nesting the transmitter 6 and receiver 7 respectively, and a channel 12 extending between the depressions and suitably shaped to receive and nest the handle 8. To provide clearance for the conductor cord 13, each of the shell sections is provided with a semi-circular notch 14 cooperative with the corresponding notch of the opposed section to form a circular aperture through which the cord 13 extends out of the shell. The shell sections are provided with a wall 16 of the minimum thickness which the particular material employed will permit while affording suitable resistance to deformation or cracking under normal pressures applied thereto in handling the instrument. For the average plastic materials, a wall thickness of about one-sixteenth of an inch has been found to give satisfactory results.

The means for securing the shell sections together and in intimate engagement with the telephone instrument, comprises a flange 17 formed integrally with and extending from the margin of one of the sections and in planar offset relation to the wall of the section so as to produce a recess 18 completely bordering the depressions 9, 11 and 12. In the surface of the recess 18, which is normal to the longitudinal dimension of the shell section, is provided a plurality of preferably circularly-shaped latch depressions 19 complementary with and adapted to receive similarly shaped protuberances 21 formed on the outer marginal portion of the opposed shell section when the latter is caused to enter the recess 18. The axial height and depth of the protuberances and latch recesses respectively which are shown in the drawing are considerably exaggerated so as to clarify the showing. The actual height of each protuberance, to produce a satisfactorily secure latch between the shell sections, need not exceed ten or fifteen thousandths of an inch while the recess is only slightly deeper. In the operation of bringing the shell sections together into interlocked relationship, the U-shaped cross sectional shape of the former will provide a desirable spring action by permitting equivalent spreading and contracting of the outer and inner telescoped rim portions of the sections as they are brought together so as to stress them with the result that when the depressions 19 and protuberances 21 are brought into registry the latter will forcibly snap into the depressions and securely hold the sections together. Although it forms a permanent part of the telephone instrument when once installed thereon, the cover shell 55 may if desired be easily removed by prying apart

the overlapped portions with a suitable thin-bladed tool so as to effect release of successive of the protuberances from the latch depressions whereupon the shell sections may be separated.

An important feature of the construction is the provision of an inturned rim flange 22 bordering each of the openings in the assembled cover shell through which the transmitter and receiver units are exposed. The rim flange extends radially inwardly of each opening and overlies the edge portion of the microphone and receiver caps so that no sharp or protruding corners are exposed which might scratch or bruise the lips, ear or other portions of the face of the user should the instrument be accidentally brushed against these body parts during use of the telephone.

The cover shell, due to its thin-walled construction does not add materially to the bulk of the telephone instrument nor render the latter unwieldy to handle. In addition, the latching arrangement for securing the shell sections together enlarges the shell only by the thickness of the flange 22 which is about equivalent to the thickness of the shell wall 16. The cover, being constructed of molded plastic, is capable of being provided in a wide variety of colors and shades with the result that numerous decorative effects and color blending of the instrument with surrounding objects may be obtained.

We claim:

1. A cover for telephone instruments of the type comprising relatively spaced transmitter and receiver units interconnected by an integral handle member, a shell for attachment on said telephone instrument formed of relatively deformation-resisting material and comprising a pair of parts completely separable each from the other, the respective parts of said shell having therein recesses cooperative when the shell parts are brought together along marginal portions of said recesses to provide a single cavity complementary in shape to and in which the instrument may be substantially completely contained and in interfitting engagement with the shell, said recesses having portions thereof cooperative when the shell parts are brought together to form openings through which portions of the transmitter and receiver are exposed, and means on said shell parts adjacent the margins of said

recesses interengageable for securing said shell parts together and retaining said parts against relative movement with respect to each other and the instrument contained therein.

- 5 2. A cover for telephone instruments of the type comprising relatively spaced transmitter and receiver units interconnected by an integral handle member, a two-part thin-walled shell for attachment on said telephone instrument, the 10 respective parts of said shell having therein recesses cooperative when the shell parts are brought together along marginal portions of said recesses to provide a single cavity complementary in shape to and in which the instrument may be substantially completely enclosed, said recesses having portions thereof cooperative when the shell parts are brought together to form circular openings through which the transmitter and receiver are operatively exposed, a flange 15 carried by one part of said shell bordering said marginal portion of a recess, said flange having therein a plurality of latch depressions, said flange further being offset in planar relation with the shell part to provide a recess bordering said 20 marginal portion of the shell part in which the marginal portion of the other shell part may be received, and protuberances carried by the latter shell part engageable in said latch depressions for connecting said shell parts together.
